UNITED STATES PATENT OFFICE.

HUDSON H. BUGELE, OF ST. LOUIS, MISSOURI.

BABY-CRIB.

1,138,451.

Specification of Letters Patent.

Patented May 4, 1915.

Application filed May 28, 1913. Serial No. 770,402.

To all whom it may concern:

Be it known that I, HUDSON H. BUGELE, a citizen of the United States, residing at St. Louis and State of Missouri, have invented 5 a new and useful Baby-Crib; and I do hereby declare the following to be a full, clear, and exact description of the invention, such as will enable others skilled in the art to which it appertains to make and use the 10 same.

This invention relates to the art of furniture, and particularly to a new and useful crib.

As an object of the invention it is the aim 15 to provide a device of this nature having folding ends, constituting portions of the head and foot ends, and a portion forming a part of the bottom of the crib, said parts being so arranged and constructed, that they 20 may be opened and attached to the side of a bed, whereby the occupant of the crib may roll from one to the other.

Another object of the invention is to provide 25 a crib, in which the bed clothing may be made up as in the usual way in the morning, and then the crib may be folded, thereby folding the bed clothing and the mattress centrally and longitudinally, after which the crib may be placed under the bed out of the 30 way.

In practical fields the details of construction may necessitate alterations, to which the patentee is entitled, provided the alterations fall within the scope of what is claimed.

35 The invention comprises further features and combination of parts, as hereinafter set forth, shown in the drawings and claimed.

In the drawings: Figure 1 is a view showing 40 the improved crib constructed in accordance with the invention and attached to the side of a bed. Fig. 2 is a sectional view on line 2—2 of Fig. 1, showing the bed clothing removed. Fig. 3 is a side view showing the legs folded. Fig. 4 is a perspective view 45 showing the crib and the bed clothing folded in such a manner so as to be placed under a bed. Fig. 5 is a sectional view on line 5—5 of Fig. 4. Fig. 6 is a view showing the crib with the legs folded and arranged on the 50 floor adjacent the wall, so that a baby can play therein.

Referring more particularly to the drawings, 1 designates a portion of the bottom of the crib, and 2 a portion of the head end 55 of the crib, while 3 denotes a portion of the foot end of the crib, whereas 4 denotes one

side of the crib. Said parts 1, 2, 3 and 4 are secured together in any suitable manner as at 5, 6, 7 and 8.

The head end 2 of the crib has hinged 60 to it as at 9 an extension end 10, while hinged at 11 to the part 3 is an extension foot end 12. Hinged at 13 to the part 1 is an extension bottom or foldable side piece 14. The extension ends 10 and 12 and the 65 extension bottom 14 may be opened and secured together by the latches 15, which are pivoted at 16 to the said extension ends. These latches are provided with notches 18, which when the crib is opened, engage the 70 lugs 19 of the extension bottom, to hold the parts secure relatively to one another. When the crib is folded the notches 18 are designed to engage the lugs 20 of the under face of the bottom 1. When the crib is 75 opened and placed adjacent a bed, the extension bottom is temporarily secured to the side bars 21 of the bed 22, by means of the straps 23, which are secured to the extension bottom, said straps having buckles 24 to receive the ends of the straps. When the crib is folded, the straps may be passed about the rails 25 and 26 of the extension ends and the extension bottom, to hold the same folded. Hinged at 27 to the crib are legs 80 28, between which and the body of the crib links 29 and 30 are connected. These links constitute means to brace and reinforce the legs, when the crib is in use, there being means 31 to prevent the links from collapsing 85 downwardly.

As shown in Fig. 4 it will be seen that the bed clothing is folded longitudinally within the crib, which is likewise folded, in order to be placed beneath the bed. When 95 it is desired to again use the crib, the same may be opened up, and the bed clothing including the mattress will fall in its proper position, the same having been made up prior to the crib being folded. If desired, 100 the legs may be folded, and the crib opened, and placed on the floor adjacent the wall as shown in Fig. 6 and secured to the wall or rather to the base board of the wall by the straps, which may be inserted through 105 staples (not shown). In this manner a baby can be left in the crib to be allowed to play therein.

The inventor is fully aware that the broad generic construction of the folding 110 crib has heretofore been devised, as shown in the patents to Carson, 926,849;

Healey, 318,111; Belsher, 432,505; Messenger, 24,880; Warfel, 839,442 and Freid, 469,131, and therefore said inventor is not claiming a broad combination, but as shown 5 in the claim he has devised a special construction, whereby a particular form of means are carried by the extension end sections to engage devices on the folding side piece and the rigid bottom piece, to hold the 10 crib either unfolded or folded, as particularly and specifically set forth in combination with the other features of the claim.

The invention having been set forth, what is claimed as new and useful is:

- 15 A folding crib, comprising a bottom, end pieces, and an immovable side piece, means for rigidly fastening said parts together, said end pieces having foldable extension end pieces hingedly connected thereto, a
- 20 foldable side piece hingedly connected to the bottom, which when folded down extends endwise between the extension end pieces, and when folded to a closed position, the extension end pieces fold thereagainst,
- 25 the corner portions of the rigidly connected end, side and bottom pieces having foldable legs, means comprising straps secured to the

foldable side piece and serving to attach the foldable side piece to the side of a bed, and also for strapping the upper parts of the 30 extension end pieces to the upper part of the foldable side piece to hold the crib folded, the outer face of the foldable side piece adjacent its outer rail having headed lugs, the bottom face of the rigid bottom 35 having headed lugs, the extension end pieces having on their lower edges latches, to engage either the headed lugs of the foldable side piece to hold the same in position, or to engage the headed lugs of the rigid bottom 40 to hold the extension end pieces folded against the outer face of the foldable side piece when the crib is collapsed, said legs adapted to be folded to permit the crib when opened to rest flat on the floor and 45 adjacent a side wall.

In testimony whereof I have signed my name to this specification in the presence of two subscribing witnesses.

HUDSON H. BUGELE.
